UNITED STATES PATENT OFFICE.

ERNEST A. BOHLMAN, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

CONDENSER.

Application filed January 29, 1923. Serial No. 615,501.

My invention relates to condensers, and has to do more particularly with variable condensers with an air dielectric, such as are now in general use in wireless sets, and an object 5 of my invention is the provision of an improved condenser of the variable type, which is provided with structural features which will facilitate assembly of a condenser of this type and, at the same time, provide an improved condenser structure which will permit the efficient operation of the same.

The condenser of my invention is of the decremeter type, in which the rotary plate element and its supporting shaft, as a whole, 15 is eccentrically located in relation to the circular fixed plates, so that the capacity of the condenser may be made to vary as the square of the angle of operation of the rotatable element, which, of course, is well known to those 20 skilled in the art.

One of the features of my invention is the provision of a simple but efficient adjustable means for limiting the longitudinal movement of the shaft carrying the movable 25 plates of the fine adjustment portion of my condenser, so that said movable plates cannot engage or touch their associated stationary plates and thereby bring about the discharge of the condenser.

Another feature of my invention is the provision of means for preventing the edges of the stationary plates and the edges of the movable plates of my condenser from being deformed, due to the different parts of my 35 condenser engaging said movable and stationary plates, when the condenser is operated to adjust said movable plates relative to said stationary plates thereby preventing any possibility of the plates engaging or touching each other to cause a short circuit of the condenser.

Still another feature of my invention is the provision of means for insuring a positively closed circuit between the rotatable shafts carrying the movable plates of my condenser.

For a more complete understanding of my invention, reference may be had to the accompanying drawing, in which like reference characters in the several views denote like parts, and in which:

Fig. 1 is a front elevation of the condenser of my invention;

Fig. 2 is a plan view of Fig. 1;

Fig. 3 is a sectional view along the line 3—3 of Fig. 2, and

Fig. 4 is a sectional view along the line 4—4 of Fig. 2.

Referring now more in detail to my invention as illustrated in the accompanying drawings, the condenser comprises a fixed plate element A and a rotatable plate element B operatively associated with the fixed plate element A. I also provide a fixed plate 60 element C, independent of the element A, and a rotatable plate element D is associated with the element C, and which element D may be moved independently of the rotatable element B.

The fixed plate element A comprises a plurality of semi-circular plates 2 of suitable metal, such as aluminum, each being provided with suitable orifices of a size to receive rods 5, 6, and 7, as shown in dotted lines on the drawing. The rods 5, 6, and 7 are inserted alternately through the suitable orifices in the plates 2 and spacer washers 8 which are made of suitable metal, and the spacer washers 8' which are made of suitable non-conducting material such as micarta or the like, which is of a lesser hardness than the hardness of the 75 plates 2, and which rods 5, 6 and 7 then have screw-threaded engagement with suitably tapped orifices in studs 9 and 10, to clamp the plates 2 in position upon said rods 5, 6, and 7. The fixed element C also comprises a group 80 of semi-circular plates 2, three in number, and which are also provided with suitable orifices. An intermediate base 11 of suitable insulation material, such as bakelite, is provided, and suitable orifices are provided in 85 said base 11 in alignment with the orifices in the plates 2, and are adapted to receive rods 13, 14, and 15 as shown in dotted lines in Fig. 1, which pass through said openings in said base 11, their threaded ends having 90 screw-threaded engagement with the tapped orifices in the studs 10. Spacer washers 8 of suitable metal, and a spacer washer 8' of suitable non-conducting material, are also provided. The rods 14 and 15 pass alternately through said metal washers 8 and plates 2, and rod 13 passes alternately through washers 8 and 8' and the orifices in the plates 2.

Referring now to element A, the insulation 105 spacer washers 8' have a greater diameter

than the diameter of the metal spacer washers 8, so that when the rotatable element B is rotated to the left to cause the plates of said rotatable element B to disengage the spaces between plates 2 of the element A, the first plate on each side of the rotatable element B will engage the peripheral edge of the washers 8', respectively, and thereby prevent the metal washers 8 from engaging the edges of the other plates of said element B to prevent short-circuiting the condenser. The spacer washers 8' are of insulating material and not only prevent short-circuiting the condenser but also prevent injury to the metal plates that contact with these washers.

The insulation spacer washer 8' on the rod 13 is adapted to engage a plate of the element D and serves for the same purpose as that described above in connection with insulation washers 8', and the plates of the rotatable element B, so that a detailed description of the same is not deemed necessary for a clear understanding.

The rotatable plate element B comprises a plurality of suitably formed plates 20, designed according to the decremeter equation for developing the boundary curve of this type of rotatable plate. The plates 20 are provided with suitable openings of a size to permit the passage of the shaft 22 of the rotatable element B associated with the fixed plate portion A of the condenser. The shaft 22 passes alternately through suitable openings in plates 20 and spacer washers 23, and when the requisite number are slipped upon the shaft 22, its end 22', which is threaded, receives a nut 24, which tightly clamps them upon the shaft 22. The plates 20 are also provided with ears 25 integrally formed therewith, which are provided with suitable openings of a size to receive a rod 27, which passes alternately through said openings 26 and spacer washers 28, which are of suitable metal, and the spacer washers 28', which are made of some suitable non-conductive material of a lesser hardness than the hardness of the plates 2 of element A. The ends of the rods 27 are threaded and are adapted to receive nuts 29, which clamp the free ends 20' of the plates 20 in the proper spaced relation to each other, and at the same time hold the plates 20 in alignment with each other upon the shaft 22. The spacer washers 28' serve for the same purpose as do washers 8', as described above; washers 28' being of a greater diameter than the diameter of the metal washers 28, will engage certain plates 2 of the element A, and prevent the metal washers 28 from engaging plates 2, so that when the rotatable element B is rotated with force to effect position of the same as shown in Figure 1, the washers 28' striking against certain plates 2 of element A, the edges of said plates 2 will not be injured and the rotatable plates 20 will not engage plates 2 to cause

a short-circuiting of the condenser. The insulation washers 28' by preventing contactual engagement of the plates of element A with washers 28 of element B, will prevent short-circuiting of the condenser.

The rotatable element D of the fine adjustment portion V of the condenser comprises a pair of plates 20 and a shaft 30, upon which the plates 20 are mounted, the plates 20 also being suitably spaced from each other by means of a metal spacer washer 28 and clamped upon the shaft 30 by means of a nut 31, which has screw-threaded engagement with the threaded end portion 30' of the shaft 30. The free ends of the plates 20 are also kept in proper spaced relation with each other by means of a suitable spacer washer 28', of non-conducting material, and a screw 32 is provided which passes through the spacer washer 28' and suitable openings in the plates 20, and nuts 33 are provided which have screw-threaded engagement with the screw 32 to clamp the plates on said screw 32. The screw 32 and nuts 33 and washers 28', in addition to holding the plates 20 in fixed spaced relation with each other, hold the plates 20 in alignment with each other on the shaft 30. The washer 28' engages the middle plate of the element C and serves for the same purpose as washers 28' of the rotatable element B, so that a detailed description of the same is deemed unnecessary.

The construction and assembly of the fixed plate elements A and C, and the rotatable plate elements B and D, having been described, I will now describe the assembly of the elements A, B, C and D, as a whole, to form the completed condenser of my invention. The intermediate base 11 is provided with a suitable orifice of a size to permit the insertion of the shaft 30, so as to bring the plates 20 of element D into position with the fixed plates 2 of the element C of the fine adjustment portion V of the condenser. When the rotatable plate element D is in this position, a base plate 37, provided with suitable orifices of a size to permit it being slipped over the threaded end portions of rods 13, 14, and 15, is provided. The protruding threaded ends of rods 13, 14, and 15 receive nuts 38 which clamp the fixed plate element C in position between the base 11 and plate 37. A terminal member 38' is provided and secured on the rod 14, between the plate 37 and nut 38, for purposes well known in the art. The shaft 30 extends through a suitable opening in the base 11, the said opening serving as an intermediate bearing for said shaft 30. The shaft 22 of the rotatable plate element B is provided with a suitable central opening extending its entire length and is of a size to permit its being slipped over the shaft 30 of the rotatable plate element D of the fine adjustment portion V of the condenser, to bring the plates 20 of said element

B into position with the fixed plates 2 of the element A, as shown in Fig. 1. To retain the plates of the element B in operative relation with the plates of the element A, a top plate 41 is provided, which plate has a suitable orifice to permit the shaft 22 to extend therethrough, and screws 43 are provided which pass through suitable orifices also provided in the plate 41 and have screw-threaded engagement with the studs 9. To provide clearance for the shafts 22 and 30 of the rotatable elements B and D, a circular area is cut from the fixed plates 2 at the point 144 and eccentrically displaced with relation to the center of the fixed plate 2. The shaft 30 of the rotatable element D of the fine adjustment portion V of the condenser extending through the suitable central opening in the shaft 22, it is clear that the said opening will serve as a bearing for the said shaft 30.

A combined thrust and frictional leaf spring 45 is provided for the rotatable plate element B, which is provided with a suitable orifice through which the shaft 30 extends. The spring 45 is arcuate in shape, and is secured to the base 11 by means of the screw 47 and nut 48, its one end being provided with an angular extending tongue (not shown on the drawing), which rests in a suitable orifice in the base 11 to prevent rotation of the said spring 45. The tension of the spring 45 is such as to bear against the bottom face of the shaft 22 to place its face in frictional engagement with the bottom face of the shaft 22, so that as the rotatable element B is rotated for tuning purposes, it will remain in any position it is set, due to this frictional engagement. The spring 45 also acts as a thrust means as the tension of the spring 45 is such as to force the shaft 22 and its parts, as a whole, upward, having reference to Figure 1; and if any downward pressure is exerted upon the shaft 22, the tension of the spring 45 is such as to prevent the shaft from being forced downward an amount sufficient to cause the rotatable plates 20 to engage the fixed plates 2 to discharge the condenser when in use. A piece 51 of suitable conducting material, having an opening in its one end through which the washer 28, secured to the shaft 30, extends, is provided, and is secured to the lower face of the plate 11 by the screw 47 and nut 48. The orifice through which the washer 28 extends is such as to cause contactual engagement between the piece 51 and said washer 28, so that a circuit will always be closed between the rotatable element D and the rotatable element B, through the medium of the washer 28, strip 51, screw 47, spring 45 to the shaft 22 of element B; and should it happen that the shaft 22 fails to make contact with the shaft 30, due to the wearing away of the parts of said shafts, or for any other reason, this will not

affect the operative relation of the elements B and D, as they are operatively associated with each other over the above traced circuit.

A combined thrust and frictional spring 54 is also provided for the shaft 30 of the rotatable element D of the fine adjustment portion V of the condenser, and serves as a frictional spring and a thrust spring, as described in connection with the spring 45 of the rotatable element B, and a further description is thought unnecessary. The spring 54 also serves as a terminal for the rotatable elements B and D to connect them with the external circuit with which the condenser is connected. The rotatable element D of the fine adjustment portion V is rotatable independently of the rotatable element B, and a knob 60 is provided, and secured to the shaft 30 by suitable means, and when grasped by the operator, may be turned, the said shaft 30 turning in the bearing in the shaft 22 formed by the opening in said shaft 22.

From the above description, it may be seen that when the dial 50 is turned, the rotatable element B is rotated independently of the shaft 30 of the rotatable element D, and when the proper tuning is accomplished through the medium of the rotatable element B in association with the fixed element A, the said element B is held in position by means of the spring 45. If a further and finer tuning is desired to clarify the incoming signals, the knob 60 is grasped and the rotatable element D is rotated until the desired result is obtained. The spring 54 is of such tension as to hold the rotatable element D at normal while the rotatable element B is rotated, and also as to overcome any friction that may be set up between the shaft 30 and the central opening in the shaft 22, when it is turned.

The shaft 30 is subject to longitudinal movement against the tension of spring 54, and should pressure be exerted against the knob 60 secured to the shaft 30, sufficiently to overcome the tension of said spring 54, said shaft will move longitudinally in a downward direction, and unless means is provided for limiting the movement of said shaft in this direction, the rotatable plates 20 of element D secured to the shaft 30 will be brought into engagement with the fixed plates 2 of element C, whereby a discharge of the condenser will be effected. Now, in order to limit the downward longitudinal movement of the shaft 30 to prevent the touching of the plates 2 and plates 20 of the elements C and D, respectively, I provide a cylindrical member 70 having a tapped orifice extending centrally therethrough, and which member 70 is suitably secured in a suitable opening in the plate 37 so that the said tapped orifice in member 70 is directly below and in alignment with the shaft 30. A screw 71 and a nut 72 are also provided, said screw having screw-threaded engagement with the nut 72 and tapped ori-

lice in the member 70. The screw 71 extends through the member 70 such a distance as not to normally engage the end of the shaft 30, but yet far enough so that it will engage the end of said shaft 30 before the plates secured to the shaft 30 will engage or touch the fixed plates of element C, when the shaft 30 is moved in a downward direction. When the proper space between the end of the screw 71 and end of shaft 30 is obtained, the nut 72 is screwed up tight against the end of the member 70 to hold said screw 71 in its adjusted position relative to shaft 30. When a different adjustment is desired, the nut 72 may be loosened and the screw 71 operated to effect another adjustment. Thus it will be seen from the above that I have provided adjustable means for limiting the longitudinal movement of the shaft 30 to prevent discharge of the condenser. By limiting the longitudinal movement of the shaft 30, it will also be seen that the shape and tension of the spring 54 is prevented from being affected by the movement of said shaft 30, for if the movement of the shaft 30 were not limited it might possibly happen that the spring 54 would be misshaped or deformed by an extreme endwise movement of said shaft 30, which would result in effecting the engagement of the plates 2 and 20 of the elements C and D.

Studs 67 and screws 68 are provided and suitably secured in the top plate 41, for permitting the condenser, as a unit, to be mounted and secured to a suitable mounting member.

While I have described and illustrated the condenser of my invention in a preferred form, it is to be understood that changes and modifications will readily suggest themselves to those skilled in the art, and I desire to cover all such changes and modifications as come within the spirit and scope of the appended claims.

Having described my invention, what I claim as new and desire to secure by Letters Patent is:

1. In a device of the character described, including a plurality of stationary members, a plurality of movable members positioned parallel to said stationary members, and operatively associated with said stationary members, a shaft for said movable members and adapted to move in a rotary and longitudinal direction, spring means for opposing longitudinal movement of said shaft and for restoring and retaining said shaft in a normal endwise position, and adjustable means for limiting the longitudinal movement of said shaft to prevent engagement of said movable members with said stationary members, and insulation means secured between some of the said plates to prevent the contactual engagement of said movable and said stationary plates when said shaft is moved in a rotary direction.
2. A device of the character described, in-

cluding a stationary element, a movable element operatively associated with said stationary element, a shaft for said movable element, a second stationary element, and a movable element associated therewith, a shaft 70 for said second movable element, said second shaft being in contactual engagement with the said first shaft whereby a circuit is closed through said shafts for said movable elements and means for effecting a circuit for said movable elements through said shafts even though said shafts fail to make contactual engagement with each other, said last means also serving to maintain the movable elements in any position to which they are operated.

3. A device of the character described, including a pair of stationary condenser plates, movable condenser plates for cooperation with said stationary condenser plates, shafts supporting said movable condenser plates, 85 said shafts adapted to be in contactual engagement with each other to close a circuit through said movable condenser plates, an independent electrical conductor connecting the sets of movable condenser plates, said conductor serving as means for maintaining said movable plates in any adjusted position.

4. In a device of the character described, including a stationary element and a movable element, said elements in operative relation with each other, and each comprising a plurality of plates, insulation means for said stationary element adapted to engage the peripheral edge of certain of the plates of said movable element to prevent contactual engagement of said stationary and movable elements, and insulation means for said movable element adapted to engage the peripheral edge of certain of the plates of said stationary element to prevent contactual engagement of said movable element and stationary element.

5. In a device of the character described, including stationary elements and movable elements, each comprising a plurality of plates and in operative association with each other, insulation means for said stationary elements adapted to engage the peripheral edge of certain of the plates of the movable elements for preventing contactual engagement of said movable elements with said stationary elements when said movable elements are in a certain position, and insulation means for said movable elements adapted to engage the peripheral edge of certain of the plates of the stationary elements for preventing contactual engagement of said movable elements with said stationary elements when said movable elements are in another certain position.

6. In a device of the character described including a plurality of stationary plates, a plurality of movable plates, said stationary plates and said movable plates being in operative association with each other and indi-

- vidual insulation means secured between certain plates of the stationary plates and between certain plates of said movable plates for preventing contactual engagement of the 5 stationary plates and the movable plates, said insulation means adapted to engage the peripheral edge of the plates of the movable elements and certain of the plates of the stationary elements.
10. 7. In a device of the character described, including a plurality of stationary plates separated by metal washers, a plurality of movable plates separated by metal washers, said stationary plates and movable plates being operatively associated with each other, insulation washers for said stationary plates for preventing contactual engagement of said movable plates with said first metal washers, and insulation washers for said 15 movable plates for preventing contactual engagement of said movable plates with said second metal washers.
8. A device of the character described, including a stationary element, a movable element for cooperation therewith supported on a shaft movable in a longitudinal and a rotary direction, individual insulating means secured in each of said elements for preventing contactual engagement of said movable 20 element with said stationary element when in certain positions, and spring means for preventing such said engagement when said shaft is moved in a longitudinal direction.
9. An electrical device of the character described, including a stationary element having a plurality of plates, a rotatable element having a plurality of plates and operatively associated with said stationary element, insulation members for said stationary element 25 of a lesser hardness than the hardness of the plates of said rotatable element and adapted to be engaged by plates of said rotatable element when the same is rotated in one direction to prevent deformity of the plates of said rotatable element, and insulation means of a lesser hardness than the hardness of the 30 plates of said stationary element and adapted to be engaged by plates of said rotatable element when the same is rotated in another direction to prevent deformity of the plates of said rotatable element, said insulation members also serving to prevent electrical connection between the plates of the stationary element and the plates of the rotatable element.
45. 10. In a device of the character described, a stationary element having a plurality of plates, a movable element having a plurality of plates, said elements operatively associated with each other, non-conducting yielding means for said stationary element for engaging the peripheral edge of certain of the plates of said movable element to prevent engagement of said first element with said second element, and to prevent deformation of
- the plates of said movable element, and non-conducting yielding means for said movable element for engaging the peripheral edge of certain of the plates of said stationary element to prevent engagement of said first and second elements, and to prevent deformation of the plates of said stationary element.
11. A condenser including 2 condenser sides; one of which is adjustable with respect to the other; a condenser plate element supplementing one of the condenser sides and mounted to turn with respect to both condenser sides; and means including a spring member for completing an electrical circuit by engaging the supplemental plate element and the condenser side supplied with this plate element.
12. A condenser including 2 condenser sides; one of which is adjustable with respect to the other; a condenser plate element supplementing one of the condenser sides and mounted to turn with respect to both condenser sides; an insulating base member located between the supplemental plate element and the said 2 condenser sides, and means including a spring member and a terminal member operative on each side of said base member for engaging the supplemental plate element and the condenser side supplied with this plate element to complete an electrical circuit between the supplemental plate element and the condenser side with which it is associated.
13. A condenser including 2 condenser sides; one of which is adjustable with respect to the other; a condenser plate element supplementing one of the condenser sides and mounted to turn with respect to both condenser sides; means engaging the supplemental plate element and the condenser side supplied with this plate element including a terminal plate against which the supplemental plate element is thrust by other spring means, all of said means, including said spring means, adapted to complete an electrical circuit.
14. A condenser including 2 condenser sides; one of which is adjustable with respect to the other; a condenser plate element supplementing one of the condenser sides and mounted to turn with respect to both condenser sides; an insulating base member located between said supplemental plate element and said 2 condenser sides, means, operative on opposite sides of said base member for engaging the supplemental plate element and the condenser side supplied with this plate element including a terminal plate against which the supplemental plate element is thrust by other spring means, said spring means adapted to maintain the adjustable element and the supplemental plate element in any position.
15. A variable condenser of the character described including a stationary element hav-

ing a plurality of stationary plates, spacing members between said plates, a rotor element for said condenser including a plurality of plates adapted to rotate between said stationary plates, an eccentrically mounted shaft for said rotor element, and means including one or more of said spacing members for preventing electrical engagement between said rotor plates and said stationary element.

16. A variable condenser of the character described including a stationary element comprising a plurality of plates, spacing members between said plates, a rotor element for said condenser including a plurality of plates adapted to rotate between said stationary plates, an eccentrically located shaft for said rotor element, one or more of said spac-

ing members being of insulating material to prevent said rotary plates from electrically engaging said stationary element.

17. A variable condenser of the character described including stationary plates and interleaved rotary plates, spacing members between said stationary plates, an eccentrically located shaft for rotating said rotor plates between said stationary plates, one of said spacing members being of insulating material to prevent electrical contact between said rotary plates and other of said spacing members.

Signed by me at Chicago, in the county of Cook, and State of Illinois, this 26th day of January 1923.

ERNEST A. BOHLMAN.
